J. C. LEWIS

WELL CASING PULLER

Filed Aug. 26, 1924

Attorney

UNITED STATES PATENT OFFICE.

JOSEPH C. LEWIS, OF FARMINGTON, NEW MEXICO.

WELL-CASING FULLER.

Application filed August 26, 1924. Serial No. 734,278.

To all whom it may concern:

Be it known that I, JOSEPH C. LEWIS, a citizen of the United States, residing at Farmington, in the county of San Juan, 5 State of New Mexico, have invented certain new and useful Improvements in Well-Casing Pullers; and I do hereby declare the following to be a full, clear, and exact description of the invention, such as will enable 10 others skilled in the art to which it appertains to make and use the same.

This invention relates to new and useful improvements in well tools, and particularly to well casing spears.

15 One object of the invention is to provide a tool which is adapted for pulling a well casing from a well.

Another object is to provide a device of 20 this character by means of which the well casing may be split or perforated.

Another object is to provide a device of this character by means of which a well casing may be straightened, or the bulges or 25 dents removed, in an operation known as "swaging."

Other objects and advantages will be apparent from the following description when taken in connection with the accompanying drawing.

30 In the drawing:

Figure 1 is an elevation of a casing spear made in accordance with the present invention, and adapted to grasp and remove a well casing.

35 Figure 2 is a vertical longitudinal sectional view on the line 2—2 of Figure 1.

Referring particularly to the accompanying drawing, 10 represents the stem of the spear, the same being tapered toward its 40 upper end, and having the pointed head 11 on its other end. Slidable on the stem 10 is a cylindrical casing 12, and formed in the wall of this casing are the longitudinally extending elongated slots 13, in each of which 45 is disposed an externally toothed block 14. The inner face of each of the blocks 14 is formed on an inclination, as indicated at 15, to correspond to the inclination or taper of the stem 10, and adapted to be engaged by 50 the stem to project the blocks through the

slots, into engagement with the interior of a well casing, upon longitudinal movement of the stem in an upward direction.

The upper end of the stem 10 is slightly enlarged, as indicated at 16, and secured at 55 their opposite ends to this enlargement 16, and to the upper end of the casing 12, are the coil springs 17, which normally and yieldably support the casing 12 in elevated position, whereby to maintain the blocks 14 60 in neutral position, or such position as will prevent them engaging the well casing.

Encircling the upper end of the stem 10, and housing the coil springs 17, is a sleeve 18, of somewhat greater diameter than the 65 stem, the upper end of this sleeve being secured to the upper end of the stem. The upper end of the stem 10 is adapted to be connected to a sucker rod, in the usual manner.

Upon letting the device down into a well casing, with a sudden downward and then a sudden upward jerk, the casing 12 will drop within the well casing, and immediately be moved upwardly by the springs 75 17, with the result that the blocks 14 will be forced out by the tapered stem, into biting engagement with the interior of the well casing, thus permitting the easy pulling of the casing from the well. The sleeve 18 serves 80 as a stop to limit the upward rebound of the casing 12. By substituting cutting blades for the blocks 14, and manipulating the device in the manner above described, slots or perforations may be formed in the well 85 casing.

What is claimed is:

1. A well casing spear including a tapered stem, a casing slidable on the stem, wedge blocks in the casing, resilient suspending 90 connections between the casing and stem, and means on the stem for engagement by the casing for limiting the movement of the casing in one direction on the stem.

2. A well casing spear including a tapered 95 stem, a casing slidable on the stem and having wedge blocks therein, resilient connections between the said casing and one end of the stem for suspending the casing, and a housing on the stem covering the resilient 100

means, said housing serving as a stop to limit the upward movement of the casing.

3. A well casing spear including a tapered stem, a casing slidable on the stem and having wedge blocks therein arranged to be projected by the stem, springs connected to the upper ends of the stem and casing whereby the casing is yieldably suspended, and a sleeve carried by the upper end of the stem in covering relation to the springs and serv-

ing as a stop against the upward movement of the casing beyond a predetermined distance.

In testimony whereof, I affix my signature, in the presence of two witnesses. 20

JOSEPH C. LEWIS.

Witnesses:

E. P. Woods,
ROBT. C. Woods.
